No. 99,426.

PATENTED FEB. 1, 1870.

W. FRANZ & W. POPE.
CIRCULAR KNITTING MACHINE.

UNITED STATES PATENT OFFICE

WILLIAM FRANZ AND WILLIAM POPE, OF CRESTLINE, OHIO.

IMPROVEMENT IN CIRCULAR-KNITTING MACHINES.

Specification forming part of Letters Patent No. 99,426, dated February 1, 1870.

To all whom it may concern:

Be it known that we, WILLIAM FRANZ and WILLIAM POPE, of Crestline, in the county of Crawford and State of Ohio, have invented certain new and useful Improvements in Knitting-Machines; and we do hereby declare that the following is a full, clear, and exact description thereof, reference being had to the accompanying drawings, and to the letters of reference marked thereon.

Figure 1 is a side elevation of the machine. Fig. 2 is a vertical section of part of the machine. Fig. 3 is a vertical section of the cylinders and other parts, showing the mode of securing parts of the machine. Fig. 4 is an elevation of a needle. Fig. 7 is a side view of the thread-carrier, the lower eye being shown in section.

Similar letters of reference indicate like parts in each of the figures.

Our improvements relate to circular-knitting machines; and our invention consists, first, in attaching the thread-carrier to a separately-revolving or oscillating cogged ring separate from the cam-cylinder, which, in our machine, is operated by the ring and not directly by the usual driving mechanism; second, in communicating motion from the ring to the cylinder by means of lugs, which permit a certain amount of motion to the ring before the cylinder is caused to move; third, in the mode of attaching the ring, bed-plate, and cams, and needle-cylinders; fourth, in the construction and arrangement of the thread-guide, thread-carrier, and take-up spring.

Special peculiarities of construction and arrangement of the parts will be set forth in the following specification and claims.

The needles and their mode of operation are the same as those commonly employed in other machines, and therefore need not be herein fully described, as all those who are skilled in the art of making and operating knitting-machines would be familiar with them.

A in the drawings represents the cylinder, upon shoulders, formed on the inner side of which the shanks *b* of the needles are supported. This cylinder revolves with the ring *B*, on which it rests. The base of the cylinder is formed, as shown in Fig. 3, with a notch, *d*, to fit over the inner edge of the ring *B*, to confine it in place, and an inwardly-projecting

flange, *R*, extending into a recess in the lower end of the needle-cylinder *Q*; the said several parts, when thus constructed, being secured to the bed-plate *P* by screws *g* passing into the lower end of the needle-cylinder. The ring *B* turns in a recess in the bed-plate, and is supported therein by means of a flange projecting from it into a depression in the bed-plate, as shown at *C* in Fig. 3. The ring *B* is actuated by a crank, *I*, and beveled pinion, the latter meshing into corresponding teeth in the lower face of the ring. The cylinder *A*, resting upon the ring and bed-plate, is made to turn with the ring, when one of the lugs *F* or *G* on its upper face engages the lug *H* on the cylinder. While the cylinder *A* is being revolved constantly in one direction in knitting circular goods, one lug on the bed-plate bears constantly against the lug *H*, but in knitting flat goods the cylinder *A* receives a reciprocating rotary movement alternately in each direction, and in this case, in order that the thread-carrier *C*, attached to the ring *B* midway between the lugs, may have the necessary movement before the action of the needles commences, the lugs *F* and *G* are set at such a distance on each side of it that the action of the inclined cam shall commence only when the thread-carrier is in the proper position relatively to the cams, at which instant the lug on the cylinder, engaged by that on the ring, causes the cylinder to begin to revolve therewith. The inside of the cylinder *A* has a shoulder, (shown in Fig. 3,) which presents a horizontal surface on which the needles rest without being moved vertically, but this shoulder falls away, as shown in Fig. 2, forming two inclined planes, first descending, to permit the needles to drop in passing over the descending incline, and then to rise in traversing the ascending inclination. At each end of the cam *K* transverse slots are made in the cam-cylinder in which the sliding guides *D* and *E* work, and which are so operated upon by the thread-carrier that in revolving the cam-cylinder in one direction or the other the forward guide shall be projected inward toward the needle-cylinder, while the rear guide is retracted into the cam-cylinder, so as to be flush with the bottom of its groove. The office of these guides is to throw up the needles, to seize the thread for making a new stitch, and

immediately on leaving it are forced down again by the face of the triangular cam J. The needles having been drawn down to make the stitch, are again raised by the ascending face of the lower cam, and on passing the other guide, which, as stated, does not now project into the cam-groove, are again supported upon the horizontal shoulder of the cam-cylinder. The sliding guides D and E extend outward through the cam-cylinder, and their external ends are beveled off in opposite directions, and the two connected by a rigid bar, D', which is centrally pivoted upon the set-screw M. The length of the sliding guides is such that, on their extreme outer ends being struck by the thread-carrier, one will be forced inward far enough to act upon the shanks of the needles, while the other one is drawn out so as to be flush with the bottom of the cam-groove. The length or looseness of the stitch is regulated by the distance between the faces of the cams J and K, and this is controlled by the set-screw M, which passes through suitable lugs on the surface of the cylinder A, and through a female screw in the arm N, which extends from the cam J outwardly through a vertical slot in the cylinder A. By turning the set-screw the cam J will be raised or lowered, the former movement shortening the stitches, and the latter lengthening them. The thread-carrier C is attached to the guard-ring B midway between the lugs F G, and they are fixed at a distance from the carrier on each side equal to the entire distance from the center of the cam K to the top of the sliding guides D E, so that in reversing the motion in knitting heels and toes, or in knitting flat goods, the thread-carrier shall be in a position opposite, or nearly so, to the highest point of the cam where it throws up the first needle to seize the thread to make a new stitch. This thread-carrier, in addition to the ordinary eye through which the thread passes, has another above it consisting of a loop or eye in the end of a bent arm, to hold the thread in a vertical position for a distance above the lower eye, so that when only part of the needles are in use and the rest of them raised, the thread, by being held out of a line drawn from the lower eye to the eye in the thread-guide T, will be prevented

from engaging with the hooks of those not in use. T is the thread-guide, through the eyes in which the thread passes. The take-up spring S is an elastic wire, coiled up at one end, and having a hook on the other end, through which the thread passes. The elasticity of the spring serves to maintain the proper tension of the thread, while the eyes in the end of the rigid arm T maintain it constantly in its proper position over the center of the circle in which the needles are placed, and around which the thread-carrier revolves.

The device for setting up the work is shown at U in Figs. 5 and 6; but no claim is here made to it, as it forms the subject of a separate application, hereafter to be filed.

Having thus described our invention, what we claim is—

1. The combination, with the cylinder A and detached cogged ring B, of the thread-carrier C, attached to the latter, and revolving a regulated distance independently of the cylinder, and all constructed substantially as set forth.
2. In combination with the cylinder A, provided with the lug H, the detached cogged ring B, having lugs F G so placed that the ring may be revolved through a portion of its arc of oscillation independently of and without communicating motion to the cylinder A, substantially as described.
3. The combination of the cylinders A and Q, detached cogged ring B, and bed-plate P, when constructed and arranged in relation to each other substantially as set forth.
4. The arrangement, in relation to each other and to the center of rotation of the machine, of the thread-carrier C, provided with the two eyes, as described, the thread-guide T, and take-up spring S, substantially as set forth.
5. The combination of the cam K, adjustable cam J, sliding guides D and E, and thread-carrier C, all constructed and operating substantially as set forth.

Signed this 15th day of January, A. D. 1870, in the presence of two subscribing witnesses.

WM. FRANZ.

WM. POPE.
